(57) **CLAIM**

The ornamental design for a gaming display, as shown and described.

DESCRIPTION

FIG. 1 is a front perspective view of a first embodiment of a gaming display, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front perspective view of a second embodiment of a gaming display, showing our new design;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof; and,
FIG. 14 is a bottom plan view thereof.

In these drawings, the solid lines illustrate the claimed ornamental design, whereas the broken lines illustrate unclaimed environmental features and form no part of the claimed design.

1 Claim, 14 Drawing Sheets
